EDWIN L. HENDERSON, OF WAUSAU, WISCONSIN, ASSIGNOR TO WILSON-HURD COMPANY, OF WAUSAU, WISCONSIN, A CORPORATION OF WISCONSIN.

DISPLAY BOARD.

Application filed June 29, 1928. Serial No. 289,112.

This invention relates to a display board in the nature of an advertising specialty and particularly designed and adapted for displaying the flavors of ice cream offered for sale.

Various types of display cabinets and devices have been proposed heretofore but none of them have measured up in a satisfactory and practical manner to the requirements 10 of a display board of the character mentioned.

Indeed, the provision of a display board suitable for this usage presents a rather difficult problem. Such a display board must be 15 of simple and compact construction and of attractive and ornamental appearance; it must have lasting qualities and above all must be susceptible of production at a low cost. Easy and economical production is 20 essential especially as advertising specialties are distributed gratuitously by merchants and manufacturers to their customers or retailers.

One of the principal objects of the invention is to provide a display board of this character which has all of these desirable and essential features in that it provides for an attractive and ornamental display of the 25 flavors of ice cream offered for sale and also attractively displays advertising matter which usually concerns the ice cream offered for sale, and in that it is of such simple and compact construction that it may be conveniently displayed on a soda fountain or the 30 like. Further, the display board is adapted to be manufactured at a comparatively slight expense from materials and by means of facilities ordinarily available. The display board is so constituted that its elements 35 may be completely formed or fashioned by simple stamping and cutting operations and may be easily and quickly assembled by utilizing a single set of fastening devices.

Other objects and advantages reside in 40 certain novel features of the construction, arrangement and combination of parts which will be hereinafter more fully described and particularly pointed out in the appended claims, reference being had to the accompanying drawings forming a part 45 of this specification, and in which:

Figure 1 is a view in front elevation showing a display board embodying the present invention;

Figure 2 is a view thereof in rear elevation;

Figure 3 is a view of the display board in edge elevation;

Figure 4 is a detail sectional view on line 4-4 of Figure 2; and

Figure 5 is a fragmentary sectional view on line 5-5 of Figure 1.

Referring to the drawings, the numeral 1 designates the front panel of the display board which is made up of sheet metal and 65 is of rectangular form. The exposed face of the panel 1 is suitably decorated and ornamental and at its upper end bears advertising matter, usually the name of the manufacturer of the ice cream, slogans, 70 trademarks, and the like. Below the advertising space at the upper end of the panel a plurality of vertically spaced and transversely extending window openings 2 are cut out or otherwise suitably formed in the 75 panel. These openings extend parallel to each other and are all of the same size and shape and may have their margins suitably decorated or ornamented. The openings 2 are slightly spaced from each other to preserve the proper strength and stiffness in 80 the front panel.

To the rear face of the front panel, a plate or sheet 3 of transparent material such as celluloid, isinglass, or the like, is applied, 85 and is of such shape and size as to be contained within the confines or margins of the front panel and yet covers all of the openings 2. In between adjacent windows 2, above the upper window 2, and below the lower window 2, sheet metal guides 5 are provided and extend transversely of the display board and parallel to each other and to the window openings 2. Each sheet metal guide 5 is presented from a sheet of metal to a 90 form of a flanged channel, the channel having a body portion 6 which lies flush against the rear face of the transparent plate or sheet 3 and having flanges 7 offset rearwardly from the plate or sheet 3 and extending parallel thereto to define guide grooves 8. At one end the guide strips have a forwardly or inwardly depressed end portion 9 providing a stop or abutment at one end of each guide groove.

Common means is provided for securing the sheet metal guides 5, the transparent plate or sheet 2, and the front panel 1 as-

sembled and preferably this fastening means consists of a plurality of eyelets 10 extending through each sheet metal guide and the adjacent portion of the sheet 3 and panel 1, the ends of the eyelets being flanged over on the guides and on the front panel. In each pair of guide grooves flanking each opening, a sign strip 12 is positioned and consists of a strip of cardboard or other material having one face suitably ornamented and bearing indicia describing the flavor of ice cream as indicated on the drawing. The subject matter of the sign strips are displayed through the window openings 2 and the strips themselves are protected by the transparent plate or sheet 3 which covers all the strips. When a strip is placed in position it may be forced over against the stops at the ends of its guide grooves and is thereby frictionally held against accidental displacement.

The panel may be provided with a hanging chain 15 having eyes 16 at its ends fastened by eyelets 17 at the top of the panel.

25 The front panel, transparent sheet, and the sheet metal guides are all so constituted as to be capable of easy and economical manufacture and in fact these parts are fashioned by a simple stamping or cutting operation. In addition, the assembly of these elements is greatly facilitated by reason of the fact that but a single fastening means is employed to secure the three parts in assembly.

30 The display board, as thus constituted, is of compact construction and does not present any objectionable bulk but on the contrary is well adapted to be received in the ordinary display spaces available around a soda fountain or other places where ice cream is dispensed or sold. The sign strips may be varied in accordance with the stock on hand and their attractive and fresh appearance is preserved by virtue of the action of the protective transparent sheet 3. The sheet metal guides contain the strips in proper position and together with the end stops facilitate the proper centering of the strips behind the window openings of the front panel.

35 50 The invention claimed is:

1. A display board comprising a front panel provided with a plurality of spaced transversely extending window openings, a single protective sheet of transparent material applied to the underside of the panel and extending across all of the openings,

double flanged sheet metal guide strips extending transversely across the rear face of the sheet adjacent said openings and providing a pair of guide grooves along the 60 margins of each window opening, common means for securing the guide strips, protective sheet and panel in assembly, and sign strips inserted in the guide grooves and having their display matter exhibited 65 through the portions of the transparent protective sheet covering the window openings.

2. A display board comprising a front panel provided with a plurality of spaced transversely extending window openings, a 70 protective sheet of transparent material applied to the underside of the panel and extending across said openings, guides extending transversely across the rear face of the sheet adjacent said openings and providing 75 a pair of guide grooves paralleling the margins of each opening and adapted to receive sign strips and common means for securing the guides, protective sheet and panel in assembly.

3. A display board comprising a front panel provided with a plurality of spaced transversely extending window openings, a protective transparent covering applied to the underside of the panel and extending 80 across said openings, guide strips consisting of flanged sheet metal channels, said guide strips extending across the rear of the panel between said openings and having the flanges forming guide grooves adapted to receive sign strips, and means for securing the panel, covering and guide strips assembled.

4. A display board comprising a front panel provided with a plurality of spaced 95 transversely extending window openings, a protective transparent covering applied to the underside of the panel and extending across said openings, guide strips consisting of flanged sheet metal channels, said guide 100 strips extending across the rear of the panel between said openings and having the flanges forming guide grooves adapted to receive sign strips, and means for securing the panel, covering and guide strips assembled, one end of each guide strip being 105 pressed inwardly toward the panel to provide stops facilitating proper position of the sign strips.

In witness whereof, I hereto affix my signature.

EDWIN L. HENDERSON.
